UNITED STATES PATENT OFFICE.

AUGUST ULRICH, OF CHARLOTTENBURG, GERMANY, ASSIGNOR TO JULIUS PINTSCH AKTIENGESELLSCHAFT, OF BERLIN, GERMANY.

RAILWAY-CARRIAGE-LIGHTING SYSTEM.

1,150,465.

Specification of Letters Patent.

Patented Aug. 17, 1915.

Application filed June 4, 1914. Serial No. 842,851.

To all whom it may concern:

Be it known that I, AUGUST ULRICH, a citizen of the German Empire, and resident of Charlottenburg, German Empire, have 5 invented a new and useful Improved Railway-Carriage-Lighting System, of which the following is a full, clear, and exact description.

In systems or plants for illuminating rail- 10 way carriages, it is necessary to provide means for adjusting the lamp to "dark" in each or any individual compartment as also for effecting the adjustment of all the lamps through the attendant at the end of the car, 15 without the necessity of his entering each compartment. This object is attained by means of the present invention, in accordance with which one feed pipe is provided for the reduced flame or "dark" adjust- 20 ment, while a second pipe is provided for the full gas feed or "light" adjustment. A cock is provided at the end of the carriage by means of which the main feed can be cut off by the attendant, so that all the lamps 25 will be supplied from the feed conduit for the reduced flames, *i. e.*, the flames will all be adjusted to "dark."

In order to meet the various requirements 30 incidental to railway carriage lighting, means must be provided in each compartment to secure a continuous gas or fuel feed to the lamp, even at the moment of turning the cock on or off. Means must also be provided for quickly blowing the air out of the 35 pipes, when the plant starts working. Furthermore reliable working of the system must be insured, however many lamps are connected up to the gasholder, and however many may be entirely cut out, or burning 40 "dark" or burning with the full flame.

The first requirement may be met either by temporarily connecting the two feed pipes to the lamp, or by providing a gas storage space in the lamp, which contains 45 sufficient fuel to keep the flame burning even when the adjustment takes place slowly.

The second requirement is met by means of a suitably constructed cock or valve in communication with both feed pipes by

means of which both conduits may be temporarily supplied with gas at normal pressure or even at a pressure above the normal in order to blow through the conduits and remove any air there may be in the same.

The third condition is fulfilled by employing a pressure throttling device, which insures a constant pressure at the outlet side of the regulator, although the consumption of gas may vary within certain limits. Thus it is necessary to substitute pressure regulators for throttling screws, both for the main and for the reduced pressure feed pipes. The present invention consists substantially in a suitable arrangement of a pressure regulating device of the class above referred to, in combination with suitable means for changing the direction of the current of gas as desired.

To attain the object in view, the low pressure or igniting feed pipe is provided with a pressure regulator for the reduced pressure and a device is mounted in the main pipe for controlling the direction of the gas passage.

The pressure regulator for the low pressure might be connected up to the gasholder direct but is advantageously connected to the outlet side of the high pressure regulator, which latter is in direct communication with the gas holder, so that the outlet pressure of the main regulator, will form the initial pressure controlled by the low pressure regulator.

At the adjusting cock the two conduits (high and low pressure) are connected to each other by means of a short connecting pipe.

The arrangement and location of the parts according to the present invention enables the connection of the main gas supply pipe to the low pressure gas supply pipe for the reduced flame to be adjusted so that the main feed may be supplied with full gas pressure and the igniting feed pipe with low pressure, or both the main feed and the low pressure feed may be supplied with low pressure gas or both feed pipes may be supplied with high pressure, which is the pres-

sure above the normal previously referred to for blowing out purposes.

In the accompanying drawings Figure 1 is a diagrammatic representation of the arrangement of pipes and lamps, and Figs. 2 and 3 are detail views showing different positions of the distributing cock or valve.

10 *a* is the gasholder, *b'* the main pressure regulator, *b''* the low pressure regulator, *e* the main pressure feed pipe to the lamps, *f* the low pressure feed pipe.

15 *d* is the distributing cock or valve mounted in the main pressure, *v* is the connecting pipe extending from this cock to the low pressure pipe *f*. *i' i''* and *i'''* are the lamps *e' f', e'', f''* and *e''' f'''* the branch pipes from the main and low pressure pipes to each lamp respectively.

20 *c c* are the cut off cocks for both feed conduits at the end of the carriage.

The upper row of lamps *g g* may be corridor lamps or the like requiring no individual adjustment.

25 The gas passes from the holder *a* through the main pressure regulator *b'* and the shut off cocks *c* to the parallelly arranged feed conductors *e f*. In the high pressure feed pipe *e* the distributing three way cock *d* is mounted, which may be adjusted to three positions. When in the position shown in Fig. 1 with the stop cocks *c* open, gas passes under normal pressure through the feed pipe *e* to the lamps, the connecting pipe *v* between pipes *e* and *f* being closed. In this 30 position of the parts any one in the compartment may adjust the compartment lamp to light or dark at will by shifting the gas feed from pipe *e* to *f* or vice versa. If the distributing cock is adjusted to the position illustrated in Fig. 2 the direct communication between the main regulator *b'* and the low pressure pipe *f* is interrupted, so that low pressure gas only will pass to the lamps through both feed conduits and 35 all lamps will burn "dark".

40 If the position of the distributing cock is adjusted to that shown in Fig. 3, both feed pipes *e* and *f* will be in communication with the high pressure regulator and pressure 45 above the normal will be available for blowing out.

50 I am aware that many systems closely resembling the present one are known and do not, therefore, make a broad claim to a system involving main lights and pilot flames.

55 I claim as my invention:

1. In a gas lighting plant for railway carriages having a gasholder and high and low pressure pipes to each lamp, the combination 60 of a high pressure regulator for the high pressure main and a low pressure regulator for the low pressure feed pipe, a distributing means mounted in the high pressure conduit and pipe connection from the same to the low pressure conduit, said distributing

device and pipes being adapted to direct the high and low pressure to supply high pressure gas to both conduits, to supply high pressure gas to the main conduit and low pressure gas to the low pressure conduit and to supply low pressure gas to both conduits substantially as described. 70

2. In a gas lighting plant for railway carriages having a gasholder and high and low pressure pipes to each lamp, the combination 75 of a high pressure regulator for the high pressure main and a low pressure regulator for the low pressure feed pipe, a three-way distributing cock mounted in the high pressure conduit and pipe connection from the same to the low pressure conduit, said three-way cock having a pipe connection to the gas main between the two regulators, said cock being provided with through-ways to open the main high pressure pipe and cut off the low pressure conduit, to cut off the main and establish communication between the low and high pressure feeds above the main cut off and to open up the main feed and simultaneously establish communication 80 between the main and low pressure pipes. 90

3. In a gas lighting plant for railway carriages having a gasholder and high and low pressure pipes to each lamp, the combination 95 of a high pressure regulator for the high pressure main and low pressure regulator for the low pressure feed pipe, a pipe connection from the inlet end of the latter to the outlet end of the former, a distributing organ mounted in the high pressure conduit and pipe connection from the same to the low pressure conduit, said distributing device and pipes being adapted to direct the high and low pressure to supply high pressure gas to both conduits, to supply high 100 pressure gas to the main conduit and low pressure gas to the low pressure conduit and to supply low pressure gas to both conduits 105 substantially as described. 110

4. In a gas lighting system, the combination 115 of a high pressure pipe; a low pressure pipe; a plurality of lamps each adapted to be fed by both of said pipes; and a distributing means communicating with both pipes for at will directing high or low pressure gas to one or both pipes. 120

5. In a gas lighting system, the combination 125 of a high pressure pipe; a low pressure pipe; a plurality of lamps each fed by both of said pipes; a pipe connection communicating with said low pressure pipe; and a distributing means communicating with the said connection and high pressure pipe for at will directing high or low pressure gas to one or both pipes. 130

6. In a gaslighting system, the combination 135 of a high pressure pipe; a low pressure pipe; a gas holder; a pressure regulator connected between the gas holder and the high pressure pipe; a pressure regulator

connected between the high pressure pipe and the low pressure pipe; a plurality of lamps each adapted to be fed by both of said pipes; and a distributing means between the regulators and the lamps for at will directing high or low pressure gas to one or both pipes.

In testimony whereof I affix my signature in the presence of two witnesses.

AUGUST ULRICH.
